UNITED STATES PATENT OFFICE.

HERBERT A. SADLER, OF SOUTH ATTLEBORO, MASSACHUSETTS.

LID LATCH.

1,414,047.

Specification of Letters Patent. Patented Apr. 25, 1922.

Application filed March 19, 1921. Serial No. 453,818.

To all whom it may concern:

Be it known that I, HERBERT A. SADLER, a citizen of the United States, residing at South Attleboro, in the county of Bristol, in 5 the State of Massachusetts, have invented a new and useful Lid Latch, of which the following is a specification.

This invention relates to improvements in lid-latches more particularly adapted for use 10 as a snap catch for locking the lids or covers of receptacles, such as ladies' hand bags, vanity cases and the like; and the object of the invention is to provide a spring-pressed catch or detent which is mounted in a celluloid frame or top portion of such a receptacle whereby the lid will be automatically locked when moved from open to closed position, the detent being so arranged as to positively lock the lid in closed position so that 15 it cannot be accidentally opened, requiring an operation by hand in order to release the lid.

With these and other objects in view, the invention consists of certain novel features 20 of construction, as will be more fully described, and particularly pointed out in the appended claims.

In the accompanying drawings:

Figure 1 is a side elevation illustrating 25 my improved latch as applied to a celluloid top for hand bags.

Figure 2 is an enlarged sectional side elevation of the top showing the lid locked in closed position by means of a detent; and 30 showing in dotted lines the lid in position to displace the detent to permit the closing of the lid.

Figure 3 is an enlarged view from the inner face of the celluloid frame, showing 35 the catch therein in which the detent is pivotally mounted.

Figure 4 is a plan view showing an edge portion of the lid, also illustrating the detent-receiving marginal notch and also the 40 recess for retaining the head of the detent when in locked position.

Heretofore it has been found difficult to provide a latch member for retaining the cover of a celluloid frame, which will be 45 strong and durable and yet which will positively lock the cover against accidental opening, also one which will work automatically to lock the lid when moved to closed position; and the following is a detailed de-

scription of one construction by which this 55 result may be accomplished:

With reference to the drawing, 10 designates the frame or top portion of a lady's hand bag, which frame is constructed of a strip of celluloid bent into the desired oblong 60 shape and its ends as secured together by the inturned edge 11 of one of the hinge plates 12, the other of which plates is connected to the under side of the lid or cover 13 to pivotally connect it to the frame. 65

The front edge of this frame is provided with a marginal slot 14 in which I have pivotally mounted a detent 15, a wire 16 being looped through the eye portion 17 of this detent with its ends 18 projecting down 70 through the frame and twisted together below the shoulder 19 to form a joint on which the detent may swing.

The outer or free end of this detent is provided with a head member 20 which is 75 preferably in spherical shape whereby it serves a double purpose; first the spherical shape is ornamental and attractive in appearance, and second, it provides a rounding under portion as at 21 to fit into a socket 80 or recessed portion 22 in the outer face of the lid. Then again the upper end 23 of this ball is curved so as to be engaged by the undercut or slanting portion 24 on the inner face of this lid so that when the lid is 85 to be closed this beveled or slanting portion 24 engages the rounding portion of the detent, pushes it forward into dotted position against the tension of the spring 25 permitting the lid to be moved to closed position 90 after which the spring 25 automatically presses the detent back into the marginal slot 26 of the lid causing its head to engage the depression 22 in its outer face, to lock the lid in closed position. 95

In order to provide a casing for the spring 25 I have provided a hollow semi-spherical member 27, the edges of which are cemented to the outer face of the frame thereby performing three functions; first, this hollow 100 member serves as a housing for the spring; second, it covers the slot 14 in the frame; and third, it serves as an ornament for the front of the frame.

In order to limit the swinging of this de- 105 tent in a backward direction I have cemented a plate 28 on the inner face of the frame so that its edge will engage the slant of the

detent and limit its inward motion, the outward or releasing motion of this detent being limited by bringing up against the upper edge of the hollow semi-spherical member 27.

My improved lid-latch for celluloid frames is extremely simple and practical in construction and by its use the lid is positively locked against accidentally opening 10 also the lid is automatically locked when moved from open to closed position.

The foregoing description is directed solely towards the construction illustrated, but I desire it to be understood that I reserve 15 the privilege of resorting to all the mechanical changes to which the device is susceptible, the invention being defined and limited only by the terms of the appended claims.

20 I claim:

1. A lid-latch comprising a frame, a detent having a shank, a lid-engaging head and pivotally mounted in said frame, a spring to swing said shank towards locked position, a 25 lid having a marginal slot for receiving the shank of said detent, said detent head being adapted to engage the outer face of said lid to hold the lid closed.

2. A lid-latch comprising a frame, a detent having a lid-engaging head and pivotally mounted in said frame, a spring for moving the detent on its pivot to normally press said detent to locked position, a lid 30 hinged to said frame and having a marginal slot in its free edge for receiving the body of the detent, a recess in the outer face of said lid for receiving and retaining said detent head to hold the lid closed and means 35 on the inner face of said lid for engaging

and temporarily displacing the detent head 40 to permit the closing of said lid.

3. A lid-latch comprising a body portion provided with a marginal slot, a lid hinged to said body, a detent including a stem pivoted in said slot and having a lid engaging- 45 head on its free end, a spring in said slot for pressing said detent to locked position in the path of said lid, a stop for limiting the movement of said detent in either locking or releasing direction, said lid being recessed 50 on its outer face to receive and retain said detent head to hold the lid closed, and an angular face on the inner face of said lid to engage and temporarily displace the detent to permit the closing of said lid to subsequently return to locked position.

4. A lid latch of the kind described comprising two movable parts adapted to be moved to closed position, a detent pivoted to one of said parts and having an enlarged 60 head on its distal end, yieldable means acting on said detent and normally tending to maintain the head of said detent in the path of the closing movement of said parts, whereby said head is engaged by the other 65 of said parts and caused to move out of normal position by the closing movement of said parts, said last mentioned part having a marginal slot therein to receive the shank of said detent when the parts are in closed 70 position and when the detent is returned to normal position by said yieldable means whereby the enlarged head of said detent engages the outer face of said slotted part to positively maintain the parts in closed 75 position.

In testimony whereof I affix my signature.
HERBERT A. SADLER.
